ABSTRACT

In a plug mill following a Mannesmann piercing mill on a seamless tube production line, a method whereby the rolled hollow shell which has been subjected to the first rolling pass is automatically rotated about its longitudinal central axis by an angle of about 90° while it is being returned to the inlet V-table of the plug mill for the second rolling pass.

11 Claims, 5 Drawing Figures

FIG. 1**FIG. 2****FIG. 3****FIG. 4****FIG. 5**## METHOD OF AUTOMATICALLY ROTATING A HOLLOW SHELL IN A PLUG MILL

BACKGROUND OF THE INVENTION

The present invention relates to a method whereby in a plug mill following a Mannessmann piercing mill on a seamless tube production line, the rolled hollow shell which has been subjected to the first rolling pass thus having fin-like sides in section, is rotated about its longitudinal central axis by an angle of about 90° before it is subjected to the second rolling pass.

In a plug mill, it has been usual to effect two rolling passes. The first rolling pass is effected by using the matching roll calibers of a given size and a plug, and the thus rolled hollow shell is rotated by an angle of 90° for the second rolling pass which is effected using the same roll calibers and replacing only the plug with another plug. In the description of this specification, the roll caliber means the shape of the grooves in each of the pair of opposed work rolls in the plug mill.

In the conventional plug mill, the bottom roll of the pair of return rolls of a return roll means located to the rear of the plug mill having a pair of work rolls is in its lowered position during the rolling operation of the plug mill. When the first rolling pass is over and the rolled hollow shell is to be returned to the inlet V-table for the second rolling pass, the top work roll of the plug mill is elevated and the bottom return roll of the return roll means is elevated by a lifting mechanism. Consequently, the rolled hollow shell is gripped firmly between the pair of return rolls so that the rotation of the return rolls returns the rolled hollow shell to the inlet V-table of the plug mill. However, since the roll caliber in each of the top and bottom work rolls of the plug mill is made circular only with respect to about 120° of its center angle and the remaining angular portions each have a relief formed therein to facilitate the rolling operation, these relief portions produce during the first rolling pass fins on both sides of the hollow shell which make the wall thickness of the shell nonuniform, and therefore it is necessary to rotate the rolled hollow shell by an angle of 90° before the second rolling pass is started so that the fin portions of the rolled hollow shell are rolled during the second rolling pass to provide a uniform wall thickness by the second rolling pass. While the rotation of such a rolled hollow shell is accomplished by means of various methods including manual methods, manual methods assisted by mechanical power and methods employing only mechanical power under electrical controls, these conventional methods respectively have their own advantages and disadvantages.

SUMMARY OF THE INVENTION

In the light of the foregoing prior art, it is an object of the present invention to provide a method of automatically rotating the rolled hollow shell in a plug mill wherein in contrast to the conventional methods in which the rolled hollow shell subjected to the first rolling pass in the plug mill is rotated after it has been returned to the inlet V-table of the plug mill by its return roll means, the rolled hollow shell is automatically rotated during its return stroke by the return roll means, resulting in lessening of the required work, reduced rolling cycle time and improved rolling efficiency.

BRIEF DESCRIPTION OF THE DRAWINGS

FIG. 1 is a general plan view showing a plug mill and return roll means as well as associated tables;

5 FIG. 2 is a front elevation showing the return roll means of FIG. 1 comprising a pair of rolls as viewed in the direction of the arrow II — II;

10 FIG. 3 is a schematic view showing the manner in which the matching roll calibers of the top and bottom return rolls of said return roll means are shifted relative to each other;

15 FIG. 4 is a sectional view showing an exemplary form of the non-driven side bearing section of the top return roll of said return roll means; and

20 FIG. 5 is a sectional view showing an exemplary form of the non-driven side bearing section of the bottom return roll of said return roll means.

BRIEF DESCRIPTION OF THE PREFERRED EMBODIMENT

25 Referring first to FIG. 1 showing the arrangement of a plug mill, return roll means 7 and an inlet V-table 3, a material converted into a hollow shell 1 by a Mannessmann piercing mill (not shown) is kicked out onto inclined skid rails 2, and the hollow shell 1 is moved forward while rolling over the inclined skid rails 2. After the hollow shell 1 has eventually fallen into an inlet V-table 3, the hollow shell 1 is pushed forward longitudinally and fed between top and bottom work 30 rolls of the plug mill 5 by a pusher 4, and it is then subjected to the first rolling pass in the plug mill 5. A bottom return roll 9 of return roll means 7 is held in its lowered position during the first rolling pass of the plug roll mill 5 and as soon as the first rolling pass is over, 35 the bottom return roll 9 of the return roll means 7 is elevated and the rolled hollow shell 1 is gripped by the top and bottom return rolls 8 and 9 which are then rotated to feed the rolled hollow shell 1 back to the inlet V-table 3 through the top and bottom work rolls of the 40 plug mill 5. In this case, the rolled hollow shell 1 is not affected by the plug mill 5, since its top work roll is in its elevated position. The rolled hollow shell is again pushed forward by the pusher 4 and it is fed to the plug mill 5 for the second rolling pass.

45 The automatic rotation by 90° of a rolled hollow shell according to the present invention is accomplished during the return stroke when the rolled hollow shell that has been subjected to the first rolling pass is returned to the inlet V-table 3 by the return roll means 7. In FIG. 50 2, the return roll means 7 automatically rotates the rolled hollow shell about 90° during its return stroke by means of its special structure including a nondriven side bearing section 10 on one end of the shaft of the top return roll 8 and a driven side bearing section 11 on the other end thereof, and a non-driven thrust locking mechanism 12 of the bottom return roll 9 for preventing the movement of the roll 9 in the direction of the center line of its shaft. In the non-driven side bearing section 10, as shown in FIG. 4, a roll shaft 17 of the top return roll 8 is mounted in roll-neck bearings 13 which are mounted in a bearing chock 14. The roll-neck bearings 13 consist of needle bearings, thus permitting the axial movement of the roll shaft 17. A pusher plate 16 formed with a threaded hole in the central portion thereof is provided on the outside of the bearing chock 14 on its center line, and a screw shaft 60 55 push rod 15 having a rotary center at one end thereof

60 on the other end thereof, and a non-driven thrust locking mechanism 12 of the bottom return roll 9 for preventing the movement of the roll 9 in the direction of the center line of its shaft. In the non-driven side bearing section 10, as shown in FIG. 4, a roll shaft 17 of the top return roll 8 is mounted in roll-neck bearings 13 which are mounted in a bearing chock 14. The roll-neck bearings 13 consist of needle bearings, thus permitting the axial movement of the roll shaft 17. A pusher plate 16 formed with a threaded hole in the central portion thereof is provided on the outside of the bearing chock 14 on its center line, and a screw shaft 65 push rod 15 having a rotary center at one end thereof

and a square turning head at the other end thereof is threadedly mounted in the threaded hole of the pusher plate 16 to move the roll shaft 17 and hence the top return roll 8 in the axial direction by the turning of the square head. Although not shown in the drawings, the driven side bearing sections 11 and 6 employ needle bearings to permit the axial movement of the associated roll shafts. The roll shaft of the bottom return roll 9 is mounted, as shown in FIG. 5, in thrust bearings 18 and 19 of the thrust locking mechanism 12 for exerting a thrust in the direction of the center line of the bottom return roll shaft, and in this way the axial movement of the bottom return roll 9 is prevented. It should be noted that it is possible to arrange the component elements of the above-described automatic shell rotating mechanism in an inverse relation relative to the top and bottom return rolls to obtain the same results.

In operation, if the screw shaft push rod 15 is turned so that the roll shaft 17 of the upper return roll 8 is moved slightly and the matching calibers of the top and bottom rolls 8 and 9 in the return roll means 7 are slightly displaced from each other (by a displacement amount A) as shown in FIG. 3, a turning moment acts on the rolled hollow shell which rotates in a direction in which the peripheral speed of the contacting rolls is great, i.e., in the clockwise direction in FIG. 3. Therefore, by suitably selecting the displacement amount A (the value of A is in the range 2-15 m/m and preferably on the order of several m/m) in consideration of various factors such as the diameter and length of a tube to be produced, the rolled hollow shell that has been subjected to the first rolling pass can be rotated during its return stroke to the inlet V-table so that the horizontal fin-like portions of the shell are placed in the desired vertical positions. The following example shows the results obtained in accordance with the method of this invention.

1. The dimensions of the tube produced: 139.7 outside diameter $\times$ 7.72 wall thickness $\times$ 10,200 length (mm)
2. Rolling plan: Dimensions after the first plug mill rolling pass-147 outside diameter $\times$ 7.9 wall thickness $\times$ 10,200 length (mm)

(3) Details of the example:

Details of return roll means:

Roll body diameter	500 (mm)
Caliber diameter	145 (mm)
Roll speed	460 (rpm)
Top roll displacement	+13 (mm)

(4) Results:

Degree of shell rotation	90 degrees $\pm$ 20 degrees
Return stroke speed	9.6 (m/sec)
Return stroke time	1.9 (sec)
Rotational speed	47.4 (degree/sec)

It will be seen from the above data that the desired results were accomplished.

While, in the above described example, the top and bottom return rolls 8 and 9 were slightly slid or displaced axially relative to each other to exert a turning moment on the rolled hollow shell, it is obvious to those skilled in the art without any detailed description that the roll shafts of the top and bottom return rolls 8 and 9 may be arranged as shown by the dot and chain lines in FIG. 1 so that the roll shafts cross each other at small angles at the center of the roll calibers through which the rolled hollow shell is passed so as to similarly exert a turning moment on the rolled hollow shell. Suitably, this crossing angle α is in the range 1 to 5°.

Therefore, it is also possible to rotate the rolled hollow shell by slightly displacing the matching calibers of the top and bottom return rolls 8 and 9 of the return roll means 7 from each other as in the above-described embodiment and by further intersecting the top and bottom return roll shafts at small angles at the center of the roll calibers through which the rolled hollow shell is passed.

It will thus be seen from the foregoing description that according to this invention, the matching roll calibers of the top and bottom return rolls 8 and 9 of the return roll means 7 may be displaced from each other by an amount A, or the roll shafts of the top and bottom return rolls 8 and 9 may be arranged to cross each other at small angles at the center of the roll calibers through which the rolled hollow shell is passed, or both of these methods may be employed together so that the contacting time between the top and bottom return rolls 8 and 9 of the return roll means 7 is controlled by means of a timer or the like to automatically rotate the rolled hollow shell by an angle of predetermined degrees during its return stroke to the inlet side of the plug mill. Further, it is possible to use additional methods such as increasing the relief portion R in each of the matching top and bottom return roll calibers to ensure a smooth automatic rotation of the rolled hollow shell or increasing the relief portion to amount to about one half of each of the matching top and bottom return roll calibers so that the fin portions of the rolled hollow shell do not impede in any way the automatic rotation of the rolled hollow shell. Thus, the present invention has among its great advantages the fact that with only a simple modification of the conventional equipment, it is possible to lessen the amount of work required for the rolling operation of tubes and thereby to ensure an increased industrial utility of the invention.

We claim:

1. In a tubular product production line including a plug mill, feed means for feeding the product to said plug mill, and return means for returning a rolled hollow shell that has been subjected to a rolling pass in said plug mill to said feed means, said return means including a pair of rotatable return rolls located at the outlet side of said plug mill, a rolling method comprising:

feeding a tube to said plug mill;
rolling said tube in said plug mill; and
engaging said rolled tube fed out from said plug mill with said pair of return rolls, and rotating said return rolls to return said engaged rolled tube back to said feed means while rotating said rolled tube by said return rolls by an angle of about 90 degrees around the longitudinal central axis of said rolled tube before said rolled tube is fed to said plug mill for a second rolling pass.

2. In the method according to claim 1, wherein said return rolls have matching opposing calibers for engaging said rolled tube therebetween, said calibers being displaced by a fixed distance relative to each other in the direction of the axes of rotation of said return rolls, whereby a turning moment is imparted to said rolled tube passing through said roll calibers upon rotation of said return rolls.

3. In the method according to claim 2 wherein said rotating step comprises rotatably driving at least one of said rolls.

4. In the method according to claim 2 wherein said return rolls are respectively located above and below said rolled tube.

5. In the method according to claim 1, wherein said return rolls have matching opposed calibers for engaging said rolled tube therebetween, comprising orienting said rolls such that the longitudinal axes of rotation of said pair of return rolls cross each other in terms of the plan view substantially at the center of said matching roll calibers between which said rolled tube is passed, whereby a turning moment is applied to said rolled tube passing through said roll calibers upon rotation of said return rolls.

6. The method according to claim 5 wherein said rotating step comprises rotatably driving at least one of said rolls.

7. The method according to claim 5 wherein said return rolls are respectively located above and below said rolled tube.

8. In the method according to claim 5, wherein said matching roll calibers of said pair of return rolls are further slightly displaced from each other substantially in

the direction of the axes of rotation thereof.

9. In the method according to claim 1, wherein said return rolls are respectively located above and below said rolled tube, said bottom return roll being fixed and said top return roll being displaced in the longitudinal axial direction thereof.

10. In the method according to claim 1, wherein said return rolls are respectively located above and below said rolled tube, said top return roll being fixed and said bottom return roll being displaced in the longitudinal axial direction thereof.

11. In the method according to claim 1, wherein said return rolls are respectively located above and below said rolled tube, at least one of said return rolls being displacable in a direction toward and away from said rolled tube, and wherein said at least one displacable roll is displaced away from said rolled tube during said feeding and rolling step, said at least one displacable roll thereafter being displaced toward said rolled tube to engage said rolled tube for return thereof back to said feeding means.
